(57) **CLAIM**

The ornamental design for a football shaped candle holder, as shown and described.

DESCRIPTION

FIG. 1 is a top perspective view of a football shaped candle holder in a closed position;

FIG. 2 is a front elevation view of the football shaped candle holder in the closed position;

FIG. 3 is a top plan view of the football shaped candle holder in the closed position;

FIG. 4 is a side elevation view of the football shaped candle holder in the closed position;

FIG. 5 is a top perspective view of the football shaped candle holder in an open position;

FIG. 6 is a side elevation view of the football shaped candle holder in the open position; and,

FIG. 7 is a top plan view of the football shaped candle holder in the open position.

The broken line shown in the drawings are for the purpose of illustrating portions of the article that form no part of the claimed design.
